SLOTTING TOOL

Filed Jan. 16, 1926

INVENTOR
FREDERICK W. ROEBBEL

By Cornwall, Bedell & James,
No. 8 S.

UNITED STATES PATENT OFFICE.

FREDERICK W. ROEBBEL, OF ST. LOUIS, MISSOURI, ASSIGNOR TO COMMONWEALTH STEEL COMPANY, OF ST. LOUIS, MISSOURI, A CORPORATION OF NEW JERSEY.

SLOTTING TOOL.

Application filed January 16, 1926. Serial No. 81,800.

My invention relates to machine tools and consists in an improved construction and arrangement of a reciprocating tool adapted to be used on planers, shapers, and slotters, or other tools using a reciprocating motion.

The main object of my invention is to provide a tool which may operate simultaneously on spaced surfaces and particularly surfaces which face in different directions.

10 This makes possible the more rapid and effective operation of the machine to which my tool is applied.

An additional object of my invention is to provide for shifting of the tool to different angles about the axis of its movement so as to permit the tool to successively cut surfaces at angles to each other without other adjustment of the machine.

15 In the accompanying drawings, I illustrate my invention as applied to a slotting machine and operating upon the pedestals of a car truck frame, and in these drawings—

20 Figure 1 is a front elevation of a slotting machine showing the truck frame mounted thereon and my cutting tool in operative position.

25 Figure 2 is a side elevation of the structure shown in Figure 1.

30 Figure 3 is an enlarged detail of the tool as seen in Figure 2 and also showing a portion of the pedestal being operated upon.

35 Figure 4 is a side view of the parts shown in Figure 3.

Figure 5 is a bottom view of the parts shown in Figure 3.

40 Figure 6 is a detail of the cutters and their mountings similar to that shown in Figure 3 but drawn on a still larger scale.

45 Figure 7 is a vertical transverse section through a cutting tool and illustrates a modification of my invention.

Figure 8 is a side view of the tool shown in Figure 7.

50 Figure 9 is a bottom view of the body of the tool shown in Figures 7 and 8 and is taken substantially on the line 9—9 of Figure 8.

55 Figure 10 illustrates the use of the tool as an ordinary cutting tool adapted to make a single cut with each stroke.

Figure 11 illustrates another modification of my invention showing the tool cutters shaped to operate on two parallel surfaces facing in the same direction.

The machine 1 may be of any ordinary slotter construction and forms no part of my present invention. It will be understood that the machine is adapted to provide vertical reciprocal movement of a rack 2 terminating in a portion 3 adapted to receive the tapered shank 4 of a cutting tool, the body of which is indicated at 5.

60 I show a car truck frame 6 mounted on the base of the machine 1 in inverted position. This frame is a one-piece casting with integral pedestals 7 and is of familiar form. It is necessary that the opposing faces of the pedestal jaws be machined parallel with each other and my improved tool enables 65 this to be done quickly and accurately.

65 A cutter holding member 8 is detachably secured to the lower end of the tool body 5 by means of a stud 9 and nut 10. The lower face of body 5 has two grooves 11 70 extending at right angles to each other and the upper face of member 2 has two corresponding ribs 12 whereby when the member is assembled with the body and nut 10 is tightened, the two parts are held against 75 relative rotation about their axis, but by loosening nut 10 the cutter holding portion of the tool may be easily shifted ninety 80 degrees in a horizontal plane and thereby adapted to plane surfaces at ninety degrees 85 to the original surfaces. Obviously the angle of change may be varied by suitable variations in the slots and ribs or the latter may be increased in number so as to take care of more than two positions of the tool. 90

95 The lower face of member 8 has a deep recess extending transversely of the member and in this recess I insert cutter holding elements 13 which are pivoted at 14 near their upper inner corners to the sides of the recess and may swing downwardly about their pivots from the position shown in full lines in Figure 3 to the position shown by dot-and-dash lines in Figure 3, the lower inner corners of the elements being beveled to accommodate such movement. It will be understood that this position of elements is taken when the tool is withdrawn after the end of a cutting stroke. 100 On the downward stroke, the upper face of the cutter is positively engaged by the bottom of the recess. Cutter bits 15 are inserted in the lower portions of elements 13 and may be individually adjusted, resharpened and removed as necessary, each being 105 110

retained by its individual set screw 31. Cutters 15 are shown in the preferred embodiment of my invention as having their cutting faces or edges extending in opposite directions to engage oppositely facing surfaces on the truck pedestal jaws.

Elements 13 are provided with laterally extending studs 16 on which are provided spring seating blocks 17 and a coil spring 18 is compressed between the pair of blocks on the same side of the tool. These cutting tools are yieldingly mounted to prevent the tools from undue dragging pressure on the return stroke which would dull the cutting edge. The springs return the cutting tools to cutting position at the end of the return stroke. In the modification shown in Figures 7, 8, and 9 I provide a sleeve 19 which surrounds the tool body 20 and its lower end 20 has a flange 21 which provides a wider supporting surface for the upper face of the cutter holding element 22 which is shown as extending laterally for a substantial distance beyond the side of the tool body. Studs 23 hold sleeve 19 against dropping of the body of the tool when member 22 is removed. The upper portion of body 20 is provided with an annular flange 24 which engages the upper end of sleeve 19 and the lower face 30 of the machine element 3, thus providing a rigid brace for the cutter holding element 22. One side of the sleeve 19 will have a suitable opening 25 provided therein to permit access to nut 26. 35 If it is desired to use the tool in the ordinary manner, element 8 or 22 may be removed and an ordinary cutting tool 27 may be inserted in the body 28 as indicated in Figure 10.

40 In Figure 11 I illustrate a modification of my invention in which the cutters 29 are pivotally mounted in a cutter holding element 30 similarly to the arrangement shown in Figures 3 to 8 but the cutters are bent 45 at right angles in such manner that their cutting edges or faces are parallel although widely spaced from each other. In this figure the tool is shown as operating on the side faces of the spaced pedestal jaws 7 of 50 the truck frame.

Obviously numerous modifications in the details of my invention may be made without departing from the spirit thereof and I contemplate the exclusive use of such 55 changes as are included in the scope of the following claims.

I claim:

1. In a tool of the class described, a body, cutters mounted on and extending laterally 60 from said body, and a sleeve surrounding said body and affording an axially facing bearing for the portions of said cutters projecting beyond the sides of said body.

2. In a tool of the class described, a body 65 having a downwardly facing shoulder near

its upper end, cutters extending laterally from the lower portion of said body, and a removable sleeve surrounding said body and seated against said shoulder and providing a bearing for the projecting portions of 70 said cutters.

3. In a reciprocal cutting tool, a body, a plurality of cutter holders mounted on said body so as to pivot in the direction of reciprocal movement, cutters in said holders, 75 means limiting pivoting of said holders in one direction about said pivots, the cutting edges of said cutters facing in same direction, and yielding means mounted on the sides of said holders for simultaneously 80 thrusting said cutters into operating position.

4. In a tool of the class described, a body having a vertical recess extending transversely thereof and a plurality of aligned 85 cutter members pivoted in said recess so as to swing downwardly from a normal position but positively held against upward movement from said position, their cutting portions extending outwardly of opposite 90 ends of said recess and facing in the same direction, and a spring mounted on and compressed between said cutter members below their pivots and outside of said body and 95 yieldingly thrusting said cutters into normal position.

5. In a tool of the class described, a body having a vertical recess in its bottom and extending from side to side of the body, a plurality of cutter holders located in said recess with aligned cutter receiving portions opening outwardly of the recess, elements 100 pivoting the upper inner corners of said holders to the sides of said recess, the upper outer corners of said holders being adapted to bear against the top of said recess, and a spring mounted on and compressed between said holders below said 105 pivots for thrusting cutters mounted in said holders into cutting position.

6. In a tool of the class described, a body having a vertical recess in its bottom and extending from side to side of the body, a plurality of cutter holders located in said recess with aligned cutter receiving portions 110 opening outwardly of the recess, elements pivoting the upper inner corners of said holders to the sides of said recess, the upper outer corners of said holders being adapted to bear against the top of said recess and the 115 lower inner corners of said holders being bevelled to permit pivotal movement downwardly of said cutters from such connecting position, and a spring mounted on and compressed between said holders below said body 120 for thrusting cutters mounted in said 125 holders into cutting position.

In testimony whereof I hereunto affix my signature this 12th day of January, 1926.

F. W. ROEBBEL.
